UNITED STATES PATENT OFFICE.

CHARLES H. HILL, OF LYNN, MASSACHUSETTS.

CUSHION AND SUPPORT FOR THE FEET.

1,271,468.

Specification of Letters Patent.

Patented July 2, 1918.

Application filed November 30, 1917. Serial No. 204,488.

To all whom it may concern:

Be it known that I, CHARLES H. HILL, citizen of the United States, residing at Lynn, in the county of Essex and State of Massachusetts, have invented certain new and useful Improvements in Cushions and Supports for the Feet, of which the following is a specification.

My invention relates to improvements in 10 cushions and supports for the feet, and more particularly to a cushion or support such as is described in United States Letters Patent #1,013,992, dated January 9, 1912, to which Letters Patent reference is hereby 15 made for a more particular description of the details such as are not herein specified, the body portion of said cushions or supports comprising a molded homogeneous elastic cellular substance.

20 Arch supporters as described and constructed according to said Letters Patent have been found to be decidedly advantageous over those heretofore in use. However when contained in boots or shoes not 25 possessing a shank of sufficient strength and rigidity to resist the weight of the wearer, the cushion in use has a tendency to cause a flattening of the boot or shoe at the shank, and thereby gives to the exterior of 30 the shoe an appearance of flat-footedness. One of the objects and purposes of my improved device is to avoid the effect mentioned by distributing the weight to the heel and ball of the shoe and thus avoid the 35 breaking down of the shank of the shoe.

It has also been found that in use the heel seat of the cushion or support has a tendency to curl out of its normal position. Another 40 of the objects and purposes of the improvements herein is to avoid this curling at the heel seat.

I accomplish the above purposes as illustrated in the accompanying drawing, in which Figure 1 shows the body portion of a 45 molded homogeneous elastic cellular substance. Fig. 2 shows a cross section of the body portion. Fig. 3 shows a weight carrying plate. Fig. 4 shows a supplementary heel portion. Fig. 5 shows my device assembled.

In Fig. 1, A shows the heel seat portion, B shows the forward portion. The line C—D shows the position of the cross section pictured in Fig. 2. E (Fig. 2) shows 55 the location of the weight carrying plate made of steel or other rigid substances

shown in Fig. 3. The plate E is so positioned within the body portion of my support, that its rear portion F rests upon the heel of the shoe in which the cushion or support is worn and its forward end G, rests upon the ball of the shoe. The weight carrying plate as a whole forms a span from the heel portion to the ball of the shoe in which it is worn, such span being intended to carry 60 the weight of the body removing the pressure from the shank of the shoe, and distributing it upon the heel and ball portion. The supplementary heel portion H (Fig. 4) comprises a plate preferably of heat proof 65 fiber, of a required stiffness, which is molded into the body portion of the cushion or support on the underside of its heel portion, at A. Both the plate E, and the supplementary heel portion H, are incorporated 70 within the body portion proper during the molding process, whereby they become firmly embedded therein and are securely held in position.

By the use of my improved device as 75 herein described, the life of the cushion or support is materially lengthened, the comfort of the user materially enhanced, and the appearance of the shoe improved, and the flat-footed effect avoided.

80 Furthermore, by providing a fiber plate or reinforcement for the relatively thin heel seat to prevent its curling, does not seriously affect the cushioning function of the thin elastic layer, as would the use of a 85 rigid metallic plate similar to the one in the thick elastic portion. In other words, the rigid or metallic plate in the thick portion has a sufficient body of elastic material above it to afford a suitable cushion which 90 is not affected by the plate, while if such a rigid plate should be embedded in the thin elastic heel seat, it would counteract 95 the cushioning effect.

Having thus described my invention what 100 I claim as new, and desire to secure by Letters Patent of the United States is:

1. A foot cushion or arch support, comprising a molded homogeneous elastic cellular body having a thin heel seat and a thick 105 intermediate portion, and a heat-proof fiber plate embedded in said thin heel seat and of sufficient stiffness to prevent said heel seat curling from normal position.

2. A foot cushion or arch support, comprising a molded homogeneous elastic cellular body having a thin heel seat and a thick 110

intermediate portion, a rigid means embedded in said thick portion to support the weight from the shank of the shoe, and a heat proof fiber plate embedded in said thin heel seat and of sufficient stiffness to prevent said heel seat curling from normal position.

3. A foot cushion or arch support, comprising a molded homogeneous elastic cellular body having at one end a relatively thin heel seat or pad and a thick narrowed portion intermediate said heel seat and its front end, a weight carrying plate of rigid material embedded in said thick narrowed portion and extending from said heel seat to adjacent its front end to span the shank portion of the shoe, and a fiber plate in said thin heel seat to prevent said heel seat curling from normal position.

4. A foot cushion or arch support, comprising a molded homogeneous elastic cellular body having at one end a relatively thin heel seat or pad and a thick narrowed portion intermediate said heel seat and its front end, a weight carrying plate of rigid material embedded in said thick narrowed portion at its lower side and extending from said heel seat to adjacent its front end to span the shank portion of the shoe, and a fiber plate embedded in the lower side of said heel seat to prevent the same from curling.

In testimony whereof I affix my signature in the presence of two witnesses.

CHARLES H. HILL.
